CLAIM

The ornamental design for the patient support cover, as shown and described.

DESCRIPTION

FIG. 1 is a perspective view of the patient support cover of the present invention;

FIG. 2 is a top plan view thereof;

FIG. 3 is a right side elevation view thereof;

FIG. 4 is an end view thereof;

FIG. 5 is a bottom plan view thereof;

FIG. 6 is a second end view thereof; and,

FIG. 7 is left side elevation view thereof.

The dashed (broken)lines shown in the drawings are included for the purpose of illustrating unclaimed portions of the patient support cover and form no part of the claimed design.
